UNITED STATES PATENT OFFICE.

ALFRED G. F. KUROWSKI, OF BROOKLYN, NEW YORK, ASSIGNOR TO UNDERWOOD TYPEWRITER COMPANY, OF NEW YORK, N. Y., A CORPORATION OF DELAWARE.

TYPE-WRITING MACHINE.

1,302,676.

Specification of Letters Patent.

Patented May 6, 1919.

Application filed March 14, 1917. Serial No. 154,650.

To all whom it may concern:

Be it known that I, ALFRED G. F. KUROWSKI, a subject of the Emperor of Germany, but having taken out his first but not his 5 final United States naturalization papers, residing in Brooklyn borough, in the county of Kings, city and State of New York, have invented certain new and useful Improvements in Type-Writing Machines, of which the following is a specification.

My invention relates to typewriting machines, and is herein disclosed as applied to tally-strip devices on an Underwood standard typewriter. Such devices are usually 15 used for preserving a tally-strip record of items on sales sheets, bills, etc., and usually include a holder both for the tally-strip itself and for the carbon paper which makes the duplicate record thereon of the original 20 on the bill or sales sheet. Such devices therefore are advantageously constructed, so as to feed the tally-strip along at each operation of the line-space mechanism; but for the purpose of making a condensed record, the 25 feeding of the tally-strip is advantageously the minimum line-space, whereas the line-spacing of the original work-sheet is often considerably larger, to enable the bill or sales sheet to present a neat appearance.

In addition to this, it is often desirable to automatically space along the tally-strip whenever a new bill or other work-sheet is inserted into the machine, as when each bill or work-sheet so inserted comprises only a 35 single item, or as when it is desired only to enter the totals of such bills,—such totals usually being written in a separate column. In such cases, it is usually desirable to advance the tally-strip only when a new work- 40 sheet is inserted, thus making the totals appear one after another close together on the tally-strip, although they may be far separated from each other in the original writing because entered on separate long work-sheets. It is also advantageous to have the 45 mounting of the roll, comprising the tally-strip and the carbon sheet therefor, as simple as possible, because such devices are often put into the hands of people entirely 50 ignorant of machinery.

With these and other objects in view, I have provided a mechanism by which the operation of a usual line-space handle may be always effective to give a uniform throw to the tally-strip, although the throw given 55 to an ordinary work-sheet may be variable. I have also found it possible to provide that this feeding may be made ineffective by the simple adjustment of a finger-piece. I have also found it possible to make each casting 60 off of the usual feed rolls effective to feed along the tally strip, and to make this feeding ineffective at will by the mere adjustment of another finger-piece.

I have also found it possible to make a 65 very simple mechanism accomplish this by providing a single pawl which may be connected to either the line-space lever or the casting-off lever, or to both.

Other features and advantages will here- 70 inafter appear.

In the accompanying drawings,

Fig. 1 is a perspective view, showing my invention as applied to the carriage of an Underwood typewriting machine. 75

Fig. 2 is a sectional view of part of the platen.

Fig. 3 is a sectional view of a clamp for catching the leading end of a tally-strip.

Fig. 4 is a side view of the tally-strip de- 80 vice.

Fig. 5 is a front view of the same.

Fig. 6 is a plan view of the typewriter carriage, showing my invention applied thereto.

Fig. 7 is a view similar to part of Fig. 4, but showing the line-space device in the act of rotating the feed roll of the tally-strip device.

Fig. 8 is a similar view, but, instead, showing the feed rolls being cast off and turning the tally-strip feed roll. 90

Fig. 9 is a view similar to Fig. 5, but showing the parts largely in section and on a larger scale. 95

Fig. 10 is a perspective view, showing the means for fastening the mandrel of the tally-strip roll.

Fig. 11 is a view similar to Fig. 8, but showing how the feed rolls may be cast off 100

without actuating the feed of the tally-strip device.

Fig. 12 is a view similar to Fig. 7, but showing the line-space device ineffective to feed the tally-strip.

Fig. 13 is an end view of the parts shown in Fig. 10.

Fig. 14 is an end view of the carbon paper roll.

10 Fig. 15 is a view similar to Fig. 4, but taken from the opposite end of the machine.

15 Fig. 16 is a sectional side view taken through the carriage adjacent the tally-strip device, and showing how the tally-strip and carbon strip are related to the work-sheet.

20 Fig. 17 is a perspective view of the devices for determining whether or not the feed roll or line-space device shall be effective to feed the tally-strip.

25 In the usual Underwood typewriter carriage, a platen 1 is fast on an axle 2 which is journaled in the end plates 3 and 4 of the platen frame of the typewriter carriage and is provided at its ends with the knobs 5 by which it may be rotated. The typewriter carriage also includes the usual front and rear feed rolls 6 and 7, which are journaled in frames 8 and 9 pivoted on a shaft 10, and are normally pressed against the platen by springs 11, so that when the work-sheet 12 is placed on the usual paper table 13 behind the platen, it may be passed down onto the apron 14 into the bite of the rear feed rolls 15 7, and thus may be fed around the platen by rotating the platen, since the front and rear feed rolls hold it against the platen.

40 The carriage includes the usual line-space lever 15 which is pivoted at 16, so that when it is thrown to the right, the bell crank extension 17 thereof strikes the turned-up end of a slide 18 to drive said slide rearwardly, causing the usual pawl 19 to engage the usual line-space wheel 20 which is fast on 45 the platen axle 2 and thereby rotate the platen. The amount of this rotation may be varied by the usual handle 21, and the end of the rotation is limited by the usual stop 22, against which a lug 23 on the pawl 50 19 strikes when it reaches the limit of its throw.

55 At the right-hand end of the carriage is located a tally-strip device which includes a pointed spindle 24, on which is mounted a roll of paper 25 adapted to be used as a tally-strip. The free end of this paper is carried down across the paper table 13 beneath the platen and up in front of the platen until its leading edge reaches a winding roll 26, said 60 roll comprising a spring 27 under which the leading edge of said strip 25 may be caught.

65 In the part of the platen occupied by the tally-strip 25, there are no pressure rolls 6 or 7, and the section of the platen around which said strip passes is free to turn on the platen

shaft 2, thus allowing the section 28 of the platen to be turned around freely by the tally-strip 25.

In order to move the tally-strip 25 along at the operation of the line-space mechanism, if such movement is desired, the roll 26 is adapted to be driven by the line-space mechanism, said roll for this purpose being fast on a shaft 29 which is journaled at its ends in the side pieces 30 and 31 of the frame supporting the mandrel 24. Near the outer end of the shaft 29, there is fast a ratchet wheel 32 which is adapted to be engaged by a pawl 33, said pawl being adapted to be driven at every operation of the line-space lever 15. To effect the drive of the pawl 33, the slide 18 of the line-space mechanism is adapted to rock a long rock shaft 34 which extends from one end to the other of the carriage, and said shaft includes a rock 85 arm 35 which may drive the pawl 33. To effect this driving, said rock arm 35 has pivoted thereto a plunger 36 provided with a slot 37, so that the plunger may slide over a guiding pin 38, with the result that when the line-space lever 15 is moved to line-space the platen, the plunger 36 moves forward and strikes a pin 39 on an oscillating plate 40 on which the pawl 33 is pivoted. The plate 40 is journaled on the shaft 29 so that 90 the pawl 33, when driven as above described, will engage with and rotate the ratchet wheel 32 and thereby carry around the winding roll 26.

The connections between the shaft 34 and the slide 18 include a link 41 which is pivoted thereto and also to a rock arm 42 fast to the shaft 34 and depending therefrom. This rearward motion of the slide 18 turns the rock arm 42 rearwardly, while the upstanding rock arm 35 at the opposite end of said shaft turns forwardly and drives the slide 36 forwardly, effecting the turning of the winding reel in a manner described. The shaft 34 is journaled in upstanding ears 43 and 44 forming part of brackets mounted on the usual cover plates 45 and 46 on the end pieces of the typewriter carriage, and said shaft lies within the usual roll edge 47 forming the upper part of the paper table 110 13. On the release of the line-space handle 15, the usual spring 48 returns the lever 15 to its normal position, and draws the slide 36 back to its normal position, shown in Fig. 8.

The same pawl 33 is utilized to turn the 120 winding roll 26 whenever the feed rolls 6 and 7 are cast off. For this purpose, it is connected to the usual casting-off finger-piece 49 which is pivoted at 50 and which casts off the feed rolls by rotating the usual cam shaft 51 to force apart the lugs 52. This connection includes the slide 54 which is adapted to underlie a forward extension 55 of the plate 40. The main part of the slide 54 lies clear of the plate 40; but a turned-up 130

lug 56 on said slide underlies the very front end of the plate 40, while the lower end of the slide is pivoted to the usual pivot 57 which connects the usual link 58 of the casting-off connections to the usual arm 59 which is operated by the finger-piece 49. The connections are such that the throwing down of the finger-piece 49 lifts the slide 54 and thereby raises the front end of the plate 40, thus drawing down the rear end thereof together with the pawl 33 and rotating the winding roll 26.

On throwing back the finger-piece 49, a spring 60 draws the plate 40 to normal position, thus throwing the pawl 33 back to its normal position. In this position, the pawl 33 is held clear of the ratchet 32 by a fixed cam 61 formed by a downward projection of the cover plate 46, (Figs. 4 and 15 17), said pawl having a downward extension 62 comprising a pin 63 which, in its normal position, lies against the front face of said cam. The rearward throw of the plate 40 by the spring 60 is limited by a 20 stop 64 which is formed as a downward extension of said plate and strikes against the front side of a rod 65 within the typewriter carriage.

If it is desired to cause the line-space lever 30 15 to be ineffective on the winding roll 26, a finger-piece 66 may be thrust rearwardly, thus carrying rearwardly a slide 67 on which it is formed, said slide having mounted therein the headed pin 38 which forms a 35 guide for the slide 36. This carries the pin 38 into the position shown in Fig. 12, in which position the slide 36 is unable to strike the pin 39 because the pin 38 holds it clear of the pin 39; therefore the operation 40 of the line-space lever at this time will be without effect on the plate 40, and consequently without effect on the winding reel 26.

In the same way, if it is desired to make 45 the operation of the casting-off lever 49 ineffective on the winding reel 26, a finger-piece 68 may be pulled forwardly into the position shown in Fig. 11, in which position the guiding pin 69 which guides the slide 54, 50 by riding in the slot 70 thereof, carries the slide in front of the end of the plate 40, thus making said slide ineffective on the plate 40, and therefore ineffective on the winding roll 26. The slides 67 and 68 are 55 shown in their normal positions in Figs. 7 and 8, in which they cause both the line-space mechanism and the roll casting-off mechanism to be effective on the winding roll 26.

60 In order to make sure that the slide 36 will not slip free of the pin 39, the end of said slide is forked, as seen at Fig. 7, so that if the slide engages the pin 39 at all, it will positively be kept from slipping to 65 either side of the pin. For the same reason

the front extension of the plate 40 has a downwardly turned cam face 72, which has a tendency to cam the slide 54 rearwardly into the bend between the cam face 72 and the main part of the plate 40, thus preventing the slide 54 from slipping free therefrom. The spring 60 is anchored in a downwardly projecting arm 73 fast to the bracket on the cover plate 46, thus keeping the spring concealed within the end plate 75 of the typewriter carriage.

The mandrel or spindle 24, on which the roll 25 is carried, is adapted to be thrust in through the wall 31 of the tally-strip device through the center of the roll 25, 80 and is long enough to extend beyond the wall 30, in which position it thrusts aside a catch 74 in the form of a slide. This catch (Figs. 9, 10 and 13) has two sides 75 and 76 cut out at 77, so that where cut out at 77, 85 the mandrel 24 may enter between the two sides 75 and 76. The slide 74 has a turned-over end 78 by which it is adapted to be pressed down against the tension of a spring 79, which normally holds the catch 74 in its 90 upper position. The catch 74 is guided by its two sides 75 and 76 in a hood 80 having tenons 82, which engage and aline within slots cut in the wall 30, said tenons also carrying a bushing 83, which extends within 95 and beyond the wall 30 and serves as a journal for the mandrel 24. In order to hold the mandrel 24 at the proper place, the sides 75 and 76 of the catch 74 engage in a circular slot 84 cut in the surface of the mandrel 100 24 and in which the sides 75 and 76 seat themselves when the catch 74 is lifted upward by its spring 79. The knurled right-hand extension 85 of the mandrel 24 is large enough to prevent the mandrel from slipping 105 too far when inserted into the opening 86 in the wall 31 in which it is journaled.

In order to make it impossible for the roll 25 to be wrongly placed on the mandrel 24, said roll 25 has a core 87, which extends 110 entirely out to one end 88 of the roll while terminating short of the opposite end thereof. When the roll is to be inserted in the tally-strip device, an end plate 89, having a bushing 90 extending therefrom and adapted 115 to complete the core for the roll 25, is inserted in the roll, and then the roll is inserted between the walls 30 and 31, with its end 88 bearing against a spider spring projection 91 which is adapted to hold the roll 120 tightly when the roll is inserted so that the core 87 bears against the margin of the opening in the spider. When thus inserted, a hub in the form of a boss 93 on the end plate 89 bears against the wall 31. The 125 mandrel passes through the end plate 89, the core 87 opening in the spider 91, and out until it engages and is caught by the catch 74. The spider 91 has its outlying spring ends bent S-shaped to catch in openings in 130

an end plate 94 which has a hub in the form of a boss 95, said hub adapted to engage the boss-bushing 83 and to be fastened thereto by a set screw 96.

5 The winding roll 26 may include a wooden body 97, which is held by a set screw 98 to its shaft 29. Said shaft is journaled in the end walls 30 and 31, and to hold it in position, it is provided with a shoulder 99 bearing against the inside of the end wall 30, and it is also provided with a collar 100 outside the end wall and lying closely against said wall, said collar being held to the shaft 29 by a set screw 101. In order to 10 provide friction to prevent the winding roll 26 from turning too easily, a spider friction spring 102 bears against the inside of the wall 30, and the outlying arms thereof bear against the flange 103 of said winding 15 roll 26.

20 In order to make it easy to catch the end of a tally-strip on said winding roll, the spring catch 27 lies in an axial slot 104 on said roll, and said spring is hinged at the 25 opposite side of said roll at 105, Figs. 3 and 5, with the result that the arc-shaped portions of the spring extending around to the hinge point furnish sufficient springiness to hold the main part of the spring in its slot 30 104, to thereby clamp the leading edge of the tally-strip. In order to make it easy to raise the spring catch, a finger-hole 107 is 35 cut out of the winding roll. The carbon paper used with these tally-strips is often in the form of a single rolled strip having two colors. In order to make sure that the typist shall insert this rolled strip correctly on its pointed mandrel or spindle shaft 108, it is provided with a core 109 which extends 40 entirely out to the left-hand side 110 thereof, but terminates short of the right-hand side 111. The right-hand side 111 is adapted to receive the hub of a flange plate 112, and, for this purpose, the wooden core is 45 provided with two axial openings 113, either one of which may engage a pin 114 which projects endwardly from the face of the flange for the purpose of entering one or the other of the holes 113, thus compelling 50 the flange to revolve with the roll.

55 Said flange plate 112 is provided with an outwardly-extending hub 115 which bears against the plate 31 and which also forms the support for a detent 116 which is adapted to lock the flange plate 112 to the mandrel 108, so that the two revolve together. The detent 116, Figs. 9 and 14, is seated in a bore 117, and is pressed inwardly by a spring 118, so that when in the proper position, said 60 detent is adapted to enter into a kerf 119 in the mandrel 108, and when thus seated, the mandrel and the flange turn as a unit. The spring 118 encircles the hub 115 and is held in place by a pin 120, which extends across 65 a cut-away segment of the hub 115.

The outer end of the mandrel 108 has suitably attached thereto a crank handle 121, by which it may revolve and the adjustments are such that when a carbon roll is in position on the mandrel 108, the turning of the 70 handle 121 will cause the detent 116 to seat itself so that the carbon roll will turn with the handle.

75 The end 110 of the carbon roll bears against a spider spring 122, which may be substantially like the spring 91, and bears against a flange plate 123, which is mounted like the plate 94 on a hub 124, and held by a set screw 125 to the internal extension of a hub 126. This hub includes a latch 127 like 80 the latch 74 and the other parts may be substantially identical so that the mandrel 108 may be released from the latch 127 which normally holds it by depressing the upper end of the latch.

85

While the paper roll 25 and the carbon roll turn freely on their shaft or mandrel, the winding roll 26 is fast to the shaft by the set screw 98.

90 In order to guide and protect the slides 67 and 68 from dust, and to prevent parts, paper, etc., from catching therein, they are beneath a cover plate 129, which is formed as a bent-over upper extension of the cover 46 at the right-hand end of the carriage. 95 The slides are also guided by fixed pins 130, which are embraced by slots 130^a on the slides.

100 In order to enable the machine to have the broadest possible utility in aiding the operative to position work-sheets thereon, it is provided with an adjustable leading end gage 131, formed as an extension of a plate 132, said plate being adjustable by screws 133, which pass through slots in said plate 105 and enter into brackets 134 and 135, which are slidably mounted on the rod 65, which is found in many Underwood typewriter carriages. The plate 132 is not only provided with the end gage 131, but also includes a 110 side gage 137 at the right-hand side thereof which may be used for adjusting a work-sheet which is to be partly or entirely clear of the tally-strip, said gage 137 usually being adjacent the edge of the tally-strip.

115 The plate 132 is adjustable longitudinally of the carriage to enable the side gage 137 to be positioned at the right position and to hold it properly positioned. The brackets 134 and 135 are provided with bent-over extensions 137^a, which are also perforated to embrace the rod 65, and where bent over, are provided with springs 138, which frictionally bear against the rod, thus taking up lost motion and preventing rattling. The 120 side gage 137 may be positioned longitudinally of the carriage to correspond with the letter-spaces thereof, and, for this purpose, the rod 65 is provided with teeth 139, which are adapted to be engaged by a tooth 140, 130

pivoted on the gage 137 and adapted to be swung into and out of said teeth by a finger-piece 141, forming an extension of said tooth.

A second side gage 142, lying on the paper 5 table 13, may be also used for positioning either the same or a separate work-sheet, said side gage being formed as a turned-up edge of a plate 143, which lies on said table, and has an upward extension 144, which 10 curves over and around the top of said paper table and which also includes an extension 145, which is pivoted in the usual manner at 146, so as to be tilttable and slidable along the table 13.

15. The platen has been described as being formed of two parts, one part 28 being freely revoluble on the other. In order to form an adequate bearing for the part 28 where it abuts against the main part of the 20 platen, and thus avoid the usual sagging of split platens, the axle 2 of the platen is provided with a sleeve 148, which is held fast to said axle by a set screw 149, said sleeve extending within the part 28 of the platen and forming a broad solid bearing for a hollow 25 sleeve 150, which is screwed fast to the wooden core 151 of the part 28 of the platen and is also supported therefrom by a collar 147. The sleeve 148 has also bearing 30 thereon a hollow sleeve 152, which forms a support for the main part of the platen, being provided with a collar 153, which engages the usual wooden body 154 of the platen, said hollow sleeve also having at the 35 opposite end a flange extension 155, through which passes a screw 156 entering the wooden core 154, thus holding said core fast to the sleeve 152; the sleeve 150 having a similar flange and screw, and also a collar 147 at the 40 end opposite the flange, both fast to the core. The sleeve 148 compels the sleeve 152 to turn with it, because the former has a lug 156^a, which closely fits an axial slot in the latter, this structure serving to facilitate assembling. The part 28 of the platen has its 45 wooden core 151 slightly spaced away from the core of the main part of the platen, so that there is a slight open space 157 between the two parts of the platen face, this being bridged over by abutting extensions 158 of the usual rubber surface of the platen. It will be seen that the short sleeve 148 strengthens the platen at the 50 critical sagging point, without materially adding to the weight of the structure. The 55 stiffness is materially added to by the girder-like structure formed by the cores 150 and 152 in their coöperation with their respective cores 151 and 154, through their collars 153 and flanges; yet this enables the sleeves 150 and 152 to be comparatively light.

The frame which comprises the side pieces 30 and 31 supporting the roll 26, etc., is adapted to be swung either into nearly up-right position, which is the normal position

shown in full lines in Fig. 15, or thrown down either forward or backward into nearly horizontal position, shown in dotted lines in said figure. This enables the rolls to be swung down when the machine is not 70 in use, thus reducing the height of the machine and enabling it to fit in an ordinary cover, or to occupy an ordinary typewriter desk, into the body of which it may slide when the cover of said desk is pulled into 75 horizontal position. In order to permit this, the side pieces 30 and 31 are journaled on the shaft 29, which shaft in turn is journaled in brackets 159.

The brackets 159 are formed as turned-up 80 extensions of a plate 160 which extends between them, thus giving rigidity to the structure. Fast to the right-hand bracket 159 is an extension collar 161, on which the side piece 31 is journaled instead of directly 85 on the shaft 29. This collar 161 is circular except at a point near the bottom but slightly in front of the bottom, at which point a hollow 162 (Fig. 4) is cut into it, which hollow is adapted to fit a detent roller 90 163, said roller being journaled very loosely in openings 164 (Fig. 9), both in the downward extension 165 of the side wall 31 and also in the upturned extension 166 of said wall, which is spaced therefrom and lies 95 against the end of the collar 161. The roller 163 is pressed strongly against the collar 161 by a broad flat spring 167, which throws the roller 163 into the hollow 162, when the roll frame is in the proper operating position. 100 The frame, however, may be swung from said position by pressure of the hand, thus forcing the roller 163 to ride out of its hollow and ride in the circular face of the collar 161. 105

In order to prevent the brackets 159 from turning on the rod 65, the shaft 29 is journaled in a fixed bracket 168 fast on the end of the typewriter carriage frame. It will be seen that the broad face of the end of the 110 collar 161 bears against the upturned extension 166, which, in turn, bears against the broad face of the ratchet wheel 32, and this ratchet wheel also bears against the bracket 168 with the broad face. These faces, therefore, adequately steady the frame in coöperation with the two bearings on the rod 65 furnished on the two brackets 159. 115

In addition to the paper table 13 and the apron 14 for the main part of the platen, the 120 separately revoluble part 28 thereof has a one-piece paper table and apron 169 of its own; this being adapted to receive both the carbon sheet and the tally-strip sheet and to guide them down under and up in front of 125 the platen. This apron is thus made in one piece in order to secure a perfectly smooth surface for the tally-strip 25 and the carbon sheet thereof to go around together. It is held somewhat tightly to the brackets 159 130

by screws 170 (Fig. 16), which pass through a turned-up extension 171 of said paper table just outside of each bracket 159.

The paper table 13 and apron 14 of the main platen extend clear out to the right-hand end of the carriage, and the auxiliary paper table 169 lies inside of these and is slightly shiftable on its screws 170, thus allowing the auxiliary table 169 to be swung either against the platen to allow a work-sheet to pass behind with the utmost freedom, or else to be swung away from the platen to allow its tally-strip and its carbon strip to be threaded through the platen.

In order to prevent the separately-revoluble part 28 of the platen from endwise movement, it is provided with a hub 172 by which it is journaled on the platen axle 2, said hub bearing against the inside of the end plate 3 of the platen frame. The main part of the platen is prevented from slipping in the opposite direction by means of the usual hub 173, which bears against the adjacent end plate of the platen frame. In order to keep the two parts of the platen sufficiently and accurately spaced from each other, to protect the overhanging portion of the rubber surface 158, the sleeves 150 and 152 are provided with short hubs 174, which have narrow bearing surfaces and therefore turn with little friction on each other.

Variations may be resorted to within the scope of the invention, and portions of the improvements may be used without others.

Having thus described my invention, I claim:

1. In a typewriting machine, the combination with a traveling carriage having a platen, of a tally strip winding roll therefor, a ratchet wheel operating said winding roll, a pawl for operating said ratchet, a line-space mechanism for said carriage, means for causing said line-space mechanism to be effective or ineffective at will, to drive said ratchet wheel by said pawl, feeding rolls adapted to coöperate with said platen, means for moving said feeding rolls to ineffective position, connections whereby said feed-roll-operating means may be made effective or ineffective at will, to drive said ratchet wheel, a shaft for said ratchet wheel, a frame carrying said winding roll and journaled on said shaft to permit the roll and frame to be swung down to the carriage, and means for holding the frame in its upper position.

2. In a typewriting machine, the combination with a traveling carriage having a platen, of a tally strip winding roll therefor, a ratchet wheel operating said winding roll, a pawl for operating said ratchet, a line-space mechanism for said carriage, means for causing said line-space mechanism to be effective or ineffective at will, to drive said ratchet wheel by said pawl, connections

whereby the line-spacing mechanism may make the line-spacing and advance of the winding roll identical or not, at will, feed rolls adapted to coöperate with said platen, means for moving said feeding rolls to ineffective position, connections whereby said feed-roll-operating means may be made effective or ineffective at will, to drive said ratchet wheel, a shaft for said ratchet wheel, a frame carrying said winding roll and journaled on said shaft to permit the roll and frame to be swung down to the carriage, and means for holding the frame in its upper position.

3. In a typewriting machine, the combination with a platen and line-spacing mechanism therefor, of a winding roll and a line-space mechanism including a plunger, a pawl for advancing said winding roll, a rocking frame carrying said pawl, a driving member operated by the line-space mechanism for the platen and connected to said plunger, a pin on said rocking frame, and means whereby said plunger may be effective or ineffective to engage said pin to rock said frame.

4. In a typewriting machine, the combination with a revoluble platen and feed rolls for coöoperating with said platen, of a winding roll, a ratchet wheel for advancing said winding roll, a pawl for operating said ratchet wheel, a slide, means adapted to cast off said feed rolls and simultaneously advance said slide, and means whereby said slide may be made effective or ineffective at will, to advance said pawl.

5. In a typewriting machine, the combination with a revoluble platen and feed rolls for coöoperating with said platen, of a winding roll, a ratchet wheel for advancing said winding roll, a pawl for operating said ratchet wheel, a slide, means adapted to cast off said feed rolls and simultaneously advance said slide, and means whereby said slide may be made effective or ineffective at will, to advance said pawl, a line-space mechanism for advancing work-sheets, a slide driven thereby, and a guide for said slide adapted to cause said slide to be effective or ineffective at will on said pawl.

6. In a typewriting machine, the combination with a traveling carriage and an end plate therefor, of line-space mechanism including a ratchet wheel adjacent said end plate, a pawl, a common axle for said pawl and said ratchet wheel, a rocking plate on which said pawl is pivoted, a plunger forming part of said line-space mechanism, and a guide-slide adapted to cause said plunger to be effective to drive said rocking plate or not, at will.

7. In a typewriting machine, the combination with a traveling carriage and an end plate therefor, of line-space mechanism including a ratchet wheel adjacent said end

- plate, a pawl, a common axle for said pawl and said ratchet wheel, a rocking plate on which said pawl is pivoted, a plunger forming part of said line-space mechanism, a 5 guide-slide adapted to cause said plunger to be effective to drive said rocking plate or not, at will, feed rolls, means for casting off said feed rolls, a drive-slide operated by said casting-off means, and a second guide-slide adapted to cause said drive-slide to be effective or not, at will, to rock said rocking plate. 10
8. In a typewriting machine, the combination with a traveling carriage and an end plate therefor, of line-space mechanism including a ratchet wheel adjacent said end plate, a pawl, a common axle for said pawl and said ratchet wheel, a rocking plate on which said pawl is pivoted, a plunger forming part of said line-space mechanism, a 15 guide-slide adapted to cause said plunger to be effective to drive said rocking plate or not, at will, a spring normally returning said plate to return said pawl to effective position, and a stop for arresting said plate. 20
9. In a typewriting machine, the combination with a traveling carriage and an end plate therefor, of line-space mechanism including a ratchet wheel adjacent said end plate, a pawl, a common axle for said pawl and said ratchet wheel, a rocking plate on which said pawl is pivoted, a plunger forming part of said line-space mechanism, a 25 guide-slide adapted to cause said plunger to be effective to drive said rocking plate or not, at will, feed rolls, means for casting off said feed rolls, a drive-slide operated by said casting off means, a second guide-slide adapted to cause said drive-slide to be effective or not, at will, to rock said rocking plate, a spring normally returning said plate to return said pawl to effective position, and a stop for arresting said plate. 30
10. In a typewriting machine, the combination with a revoluble platen and a travelling carriage, of a paper table and apron for said platen, a roll-holder, a separate paper table and paper apron for said holder lying between said platen and platen-apron and 35 table, and a mounting for said roll-holder apron adapted to permit it to swing to and from the platen. 40
11. In a typewriting machine having a platen frame including ends, the combination with a revoluble platen and a rod between said ends, of brackets upon said rod, a tally-strip roll journaled upon said brackets, and a bracket upon one of said ends of 45 steadyng the first-named brackets. 50
12. In a typewriting machine having a platen frame including ends, the combination with a revoluble platen, and a rod between said ends, of brackets upon said rod, 55 a tally-strip roll journaled upon said brackets, a bracket upon one of said ends of steadyng the first-named brackets. 60
- a tally-strip roll journaled upon said brackets, a bracket upon one of said ends for steadyng the first-named brackets, a shaft for said tally-strip roll, a frame journaled upon said shaft, a second roll in said frame, and means for detaining said frame in an upright position when swung upright. 65
13. In a typewriting machine having a platen frame including ends, the combination with a revoluble platen, and a rod between said ends, of brackets upon said rod, a tally-strip roll journaled upon said 70 brackets, and a bracket upon one of said ends for steadyng the first named brackets, said platen comprising two separately revoluble portions, one of said portions being adjacent the tally-strip roll and adapted to turn with the moving tally strip. 75
14. In a typewriting machine having a platen frame including ends, the combination with a revoluble platen, and a rod between said ends, of brackets upon said rod, a tally-strip roll journaled upon said 80 brackets, a bracket upon one of said ends for steadyng the first-named brackets, a shaft for said tally-strip roll, a frame journaled upon said shaft, a second roll in said frame, and means for detaining said frame in an upright position when swung upright, said platen comprising two separately revoluble portions, one of said portions being adjacent the tally-strip roll and adapted to turn with the moving tally strip. 85
15. In a typewriting machine having a platen frame including ends, the combination with a revoluble platen, and a rod between said ends, of brackets upon said rod, a tally-strip roll journaled upon said 90 brackets, a bracket upon one of said ends for steadyng the first-named brackets, a shaft for said tally-strip roll, a frame journaled upon said shaft, a second roll in said frame, and means for detaining said frame in an upright position when swung upright, said platen comprising two separately revoluble portions, one of said portions being adjacent the tally-strip roll and adapted to turn with the moving tally strip. 95
16. In a typewriting machine, the combination with a platen and line-spacing mechanism therefor, of a winding roll, line-spacing mechanism for said roll including a 100 plunger, a pawl for advancing said winding roll, a rocking frame carrying said pawl, a driving member operated by the line-spacing mechanism for said platen, a pin on said rocking frame, a guide for said plunger, a 105 frame journaled upon said shaft, means for detaining said frame in an upright position when swung upright, and means adapted to be made effective at will for turning said tally-strip roll at the manipulation of a work-sheet relatively to the 110 platen. 115
17. In a typewriting machine, the combination with a platen and line-spacing mechanism therefor, of a winding roll, line-spacing mechanism for said roll including a 120 plunger, a pawl for advancing said winding roll, a rocking frame carrying said pawl, a driving member operated by the line-spacing mechanism for said platen, a pin on said rocking frame, a guide for said plunger, and means whereby said guide may cause said plunger to move idly or not, at will. 125
